UNITED STATES PATENT OFFICE

CLAY WEESNER, OF NEWCASTLE, INDIANA, ASSIGNOR TO THE HOOSIER MANUFACTURING COMPANY, OF NEWCASTLE, INDIANA, A CORPORATION OF INDIANA

EXTENSION-TABLE LOCK

Application filed January 28, 1928. Serial No. 250,166.

This invention relates to tables having extension tops whereby one or more leaves may be removably added to secure a larger top area. It is the particular object of this invention to provide a locking means whereby the movable top sections may be secured in selective positions to prevent accidental opening of the top.

The following is a description of one particular form of the invention as shown in the accompanying drawing, in which—

Fig. 1, is a fragmentary top plan view of an extension top table embodying my invention;

Fig. 2, a fragmentary side elevation of the table;

Fig. 3, a transverse vertical section on an enlarged scale on the line 3—3 in Fig. 1;

Fig. 4, a longitudinal vertical section on an enlarged scale on the line 4—4 in Fig. 1; and

Fig. 5, a transverse vertical section on the line 5—5 in Fig. 4.

Like characters of reference indicate like parts throughout the several views of the drawings.

I form a table skirt 10 supported by the legs 11 and having the side rails in one piece. A center rail 12 is centrally supported between the skirt ends to have its top face 30 slightly above the skirt top. Each vertical face of the rail 12 has a longitudinal dove-tail groove 13 cut therein to slidably receive therein the correspondingly shaped tenons 14 and 15 of the slides 16 and 17 respectively so that the slides may not be displaced laterally from the rail 12 but are free to slide longitudinally along the rail, one on each side.

At the center on the top face of the rail is pivotally mounted a spur gear 18 to have its top face flush or slightly below the top of the rail 12. A rack bar 19 is secured to each slide 16 and 17 to have its teeth mesh with the spur gear 18 so that as one slide 16 is moved along the rail 12 the other slide 17 is moved in the opposite direction by the gear 18.

A top section 20 is secured to the top face of the slide 16 toward its outer end, and a similar top section 21 is secured to the slide 17.

In addition to being supported on the slides

16 and 17 the top sections rest on castors 22 projected upwardly from the inner sides of the skirt ends so that the top sections may be moved toward and away from each other very easily. By pulling out on the top section 20, the top section 21 is correspondingly carried outwardly in the opposite direction and the desired number of table leaves 23, here shown as two in number, may be laid across the skirt sides between the sections 20 and 21, and the sections then be moved inwardly to grip the leaves therebetween, dowel pins 24 being employed in the usual and well known manner, but as the top sections 20 and 21 are so free to be moved, a slight pull on either section 20 or 21 would cause an opening to be formed therebetween, and I supply a simple, effective means for securing the sections 20 and 21 in the desired positions.

This means comprises a lever 25 pivoted to rock in a vertical plane near one end on the side of the rail 12 where it will not be contacted by the slide 17. The lower end of the lever 25 carries a foot 26 which passes under the rail 12 to extend across under the slide 16 in the path of the downwardly hanging bar 27 which is attached to the outer face of the slide 16. This bar 27 is formed to have a plurality of notches 28 cut in its lower edge, these notches being spaced apart a distance equal to half the width of each of the table leaves 23.

The foot 26 is normally pressed against the bar 27 to enter these notches 28 as slide 16 is moved, by reason of the tension spring 29 engaged by one end in the top end of the lever 25 and by the other end on the post 30 secured in the rail 12. (Fig. 4.) The notches 28 are formed to have vertically disposed faces at the inner sides of the notches toward the center of the table and sloping faces therefrom outwardly, back down to the under edge of the bar 27 whereby the top section 20 may be pushed inwardly but cannot be pulled outwardly without the lever 25 being rocked to throw the foot 26 down out of the notch 28.

A rod 31 is pivotally attached to the lever 25 just below the spring 29 and horizontally extended out slidably through the skirt end

to carry a knob 32 on its outer end. By pushing in on the knob 32, the lever 25 may be rocked to disengage the foot 26 from the notches 28.

5 Since one slide 16 can not move independently of the other slide 17, the locking means above described is applied to but the one slide 16, the slide 17 being secured in association with the slide 16 by reason of the intermediate gear 18.

What I claim is:

1. In a table having a top in two slidably united members, a skirt, a fixed rail, means for correspondingly sliding the other top member in an opposite direction when one of the top members is slidably moved, a lever pivoted to the rail having a foot, a plate carried by one of the table top members having one or more notches to engage the foot of the lever and prevent outward movement of the top member, a spring pressing the lever into lock and manually operative push rod release means.

25 2. In a table having a top in two slidably united members, a skirt, a fixed rail, means for correspondingly sliding the other top member in an opposite direction when one of the top members is slidably moved, a lever pivoted to the rail having a foot, a plate carried by one of the table top members having one or more notches to engage the foot of the lever, said notches having vertically disposed faces on their sides toward the center of the table sloping opposite faces, and 30 a spring influencing the lever to normally press its foot into lock with the notches of the bar and manually operated push means for unlocking it.

3. In a table having a top in two slidably united members, a skirt, a fixed rail, means for correspondingly sliding the other top member in an opposite direction when one of the top members is slidably moved, a lever pivoted to the rail having a foot, a plate carried by one of the table top members having one or more notches to engage the foot of the lever, said notches having vertically disposed faces on their sides toward the center of the table and sloping opposite faces, 45 and a spring influencing the lever to normally press its foot into lock with the notches of the bar, and a manually operated means extending outside of the skirt from the lever to move the lever in the direction to release 50 its foot from the notched bar.

4. In a table having a top in two slidably united members, a skirt, a fixed rail, means for correspondingly sliding the other top member in an opposite direction when one of the top members is slidably moved, a lever pivoted to the rail having a foot, a plate carried by one of the table top members having one or more notches to engage the foot of the lever, said notches having 55 vertically disposed faces on their sides to-

ward the center of the table and sloping opposite faces, and a spring influencing the lever to normally press its foot into lock with the notches of the bar, and a bar attached to the lever and passing through the skirt 70 and terminating with a knob.

In testimony whereof I affix my signature.

CLAY WEESNER.
